DESIGN FOR AN ICE CREAM FREEZER

James W. Townsend, Winchendon, Mass., assignor to The Alaska Freezer Co., Inc., Winchendon, Mass., a corporation of Massachusetts

Application May 29, 1937, Serial No. 69,619

Term of patent 14 years

To all whom it may concern:

Be it known that I, James W. Townsend, a citizen of the United States, residing at Winchendon, in the county of Worcester and State of Massachusetts, have invented a new, original, and ornamental Design for an Ice Cream Freezer, of which the following is a specification, reference being had to the accompanying drawing, forming part thereof.

Fig. 1 is a front elevation of the ice cream freezer showing my new design;

Fig. 2 is a top plan view thereof;

Fig. 3 is a partial side elevation thereof taken in the direction of the arrow 3 in Fig. 1; and

Fig. 4 is a partial side elevation of the freezer handle taken in the direction of the arrow 4 in Fig. 1.

I claim:

The ornamental design for an ice cream freezer as shown.

JAMES W. TOWNSEND.
